UNITED STATES PATENT OFFICE.

FREDERICK B. RISING, OF ANTRIM, NEW HAMPSHIRE, ASSIGNOR TO
GOODELL COMPANY, OF SAME PLACE.

FORK.

SPECIFICATION forming part of Letters Patent No. 674,344, dated May 14, 1901.

Application filed July 10, 1899. Serial No. 723,280. (No model.)

To all whom it may concern:

Be it known that I, FREDERICK B. RISING, of Antrim, county of Hillsboro, State of New Hampshire, have invented an Improvement 5 in Forks, of which the following description, in connection with the accompanying drawings, is a specification, like letters on the drawings representing like parts.

This invention has for its object to improve 10 the knife-guard of forks used as complemental to a carving-knife. The guard is composed of a forked lever pivoted upon and surrounding the shank of the fork. Heretofore various devices have been employed for 15 retaining this guard in its operative position to act as a shield for the knife.

My invention herein contained relates more especially to a novel means for keeping the guard in its operative position.

20 The novel means devised by me consists, essentially, of two short studs located, respectively, in and extended from the opposite ends of a hole made through the shank, a spiral spring being located in said hole, the 25 opposite ends of the spring acting, respectively, upon the two pins, so that said pins are normally so acted upon by the spring that their ends are forced outwardly from the opening of the shank, said pins coacting with inclines at the inner sides of the forked part of 30 the guard, keeping the guard either in its active position or in its closed position.

Figure 1 of the drawings shows a fork with the guard in its operative position. Fig. 2 35 shows a section through the fork in the line x to represent the pins in their operative position; and Fig. 3 shows the guard in upright position, the shank being shown on the section-line x' , Fig. 1.

40 The fork A may have any desired number of tines, preferably two, said tines extending from a shank A', provided with a suitable handle B, of any usual material and shape. The guard C is forked at its lower 45 end at C', and the guard is mounted on the shank of the fork by means of a pivot-pin a , extended through the shank. The inner sides of the forked part of the guard are beveled, as best shown in Fig. 2, in opposite directions 50 from a center point.

The parts above referred to are and may be all as usual in forks.

In accordance with my invention I have bored a hole b entirely through the shank substantially parallel with the pivot a and 55 below it. In this hole I place a spiral spring c and at the opposite ends of said spring suitable pins $c^2 c^3$. The free ends of these pins act against one or the other incline at the inner sides of the forked part C' of the 60 guard C, and the said spring is always compressed, so that it exerts at its opposite ends outward pressure on both the pins $c^2 c^3$, so that they are always kept in operative position with relation to the faces of the forked 65 part of the guard.

The drawings, Figs. 1 and 2, show the guard erect in its operative position, with the points of the pins working against the inclined faces of the guard at the right of the dotted line x' . 70

When the guard is turned to the left viewing Fig. 1, in order that the guard may substantially fit the shank, as when the fork is not in use, the thickest portion of the forked part of the guard acting upon the ends of the 75 pins $c^2 c^3$ pushes said pins into the hole b , compressing the spring; but as soon as the thickest part of the forked end of the shank has passed the said pins the spring immediately throws them out that they may coöperate with 80 the opposite inclined parts of the guard, maintaining the guard in its closed or inoperative position.

It will be seen upon inspection of Fig. 2 85 that my fork includes a pivoted guard provided with oppositely-disposed beveled faces and a spring-actuated pin carried by the fork and adapted to alternately engage each of the beveled faces for the purpose of firmly holding said guard in its respective extreme positions. To shift the guard, it is simply necessary to apply a comparatively light pressure thereto, which causes the spring-actuated bolt to enter its seat in the shank of the fork. It will be evident also that both 90 95 branches of the guard are furnished with these beveled faces, and they are arranged in pairs to operate in unison against two pins normally pressed outward by a single spring acting against the ends thereof.

Having described my invention, what I claim, and desire to secure by Letters Patent, is—

A fork having a transverse hole made completely through its shank portion, a bifurcated guard pivoted on and straddling said shank near said transverse hole, the branches of said bifurcated guard each having oppositely-inclined beveled faces, two pins slidably fitted in said hole, a spring fitted between the pins and bearing against their in-

ner faces to force them outward equally on both sides of the shank and cause the outer ends of the pins to bear against the beveled faces of the bifurcated guard.

In testimony whereof I have signed my name to this specification in the presence of two subscribing witnesses.

FREDERICK B. RISING.
